UNITED STATES PATENT OFFICE.

THORNYCROFT DONALDSON, OF WOOLSTON, ENGLAND.

FURNACE FOR BURNING PULVERIZED FUEL.

1,411,846.

Specification of Letters Patent.

Patented Apr. 4, 1922.

Application filed March 18, 1920. Serial No. 366,868.

To all whom it may concern:

Be it known that I, THORNYCROFT DONALDSON, a subject of the King of Great Britain and Ireland, residing at Woolston, in the county of Hants, England, have invented Improvements in or Relating to Furnaces for Burning Pulverized Fuel, of which the following is a specification.

This invention relates to steam generators adapted to be fired with pulverized fuel and it has for its object to provide an improved form of furnace and fuel introducing means.

To this end, the invention consists in arranging that the fuel shall be directed in sheet form against an abutment in order that eddies may be produced tending to facilitate complete combustion of the fuel. Preferably a nozzle is employed which will cause the fuel to be discharged more or less 20 in the form of a hollow cone, the abutment being more or less annular in shape.

In the accompanying drawings, Fig. 1 shows partly in end elevation and partly in section on the line I—I of Fig. 2, one construction of steam generator embodying the invention, the walls and some of the flues necessary to provide passages for the products of combustion, being omitted. Fig. 2 is a longitudinal section of the steam generator corresponding to the line II—II of Fig. 1, also with the walls and some of the flues omitted. Fig. 3 is a view to a larger scale than Figs. 1 and 2, of the fuel injecting nozzle. Fig. 4 is an end elevation corresponding thereto and Fig. 5 is a central horizontal section of the same. Figs. 6, 7 and 8 are sections illustrating modifications.

Referring first to Figs. 1 to 5, a furnace *a* is employed having a floor or bottom portion *b* which is inclined forwardly towards the burner *c* so that any molten slag formed and resulting from the melting of the ashes from the pulverized fuel burnt, may gravitate to the front of the furnace, or be easily removed by mechanical means. *d* is the abutment of arcuate shape located about midway between the front and rear ends of the furnace. It is almost annular in shape but is interrupted by a gap *e* at the bottom, so as not to interfere with the flow or removal of slag. The burner *c* comprises a pipe *f* having a flared or conical discharge end or nozzle *g* into which is fitted a conical or tapered member *h* such as to produce an annular orifice through which the fuel is discharged, so that it issues in

the form of a hollow cone. In order that the fuel may not be discharged into the gap *e* in the abutment *d*, a deflector or obstructor *h'* may be fitted in the nozzle so as to produce a corresponding gap in the conical film or layer of fuel discharged therefrom.

The combination of a burner such as described with an arcuate abutment as shown, ensures a uniform combustion of fuel, thereby preventing undue admission of cold air. The furnace wall, including the floor or bottom portion *b*, and also the abutment *d*, are shown as composed of refractory material.

If desired, the discharge orifice of the nozzle may be provided with internal guides, deflectors, or baffles of a helical or other suitable form to control the flow of the discharged layer of fuel, one such guide being shown at *j* in the discharge orifice *g'* between the flared pipe *f'* and tapered member *h'* Fig. 6, and, in some cases, the nozzle may be constructed of a pipe *f''*, tapered member *h''* and interposed annular member *f'''* so as to produce passages *g''* and discharge more than one layer of fuel as shown in Fig. 7. Also, as shown in Fig. 8, the nozzle comprising parts *f'', h'', g''* may be water jacketed to keep it cool, when necessary.

The steam generator to which such an arrangement may be applied, may be of any suitable form, it being preferred, where one or more such furnaces is or are incorporated within a steam generator shell *k* having smoke tubes *m* above such furnace or furnaces, as in a marine type of boiler, such as is shown in the example taken, to extend the furnace or furnaces as at *n* in front of the boiler, so that the fuel shall be well 95 afame near such front and the furnace at a high temperature throughout, thereby keeping the slag fluid and capable of easy removal.

What I claim is:—

1. In a steam generator, a cylindrical furnace lined with refractory material, an abutment of refractory material made of arcuate shape located between the front and rear ends of said furnace, the gap between the ends of said abutment being located near to and extending to the floor of said furnace and a fuel nozzle having a flaring orifice adapted to discharge pulverized solid fuel in the form of a backwardly and outwardly spreading hollow stream against said abutment.

2. In a steam generator, a cylindrical furnace lined with refractory material and having at its rear portion a forwardly and downwardly sloping bottom of refractory material, an abutment of refractory material made of arcuate shape, located between the front and rear ends of said furnace and having its ends spaced a short distance apart to form a narrow gap located near to and 10 extending to the floor of said furnace and a fuel nozzle having a tubular flaring outlet adapted to discharge pulverized solid fuel in the form of a backwardly and outwardly spreading hollow stream against said abutment.

3: In a steam generator, a cylindrical furnace having a forwardly and downwardly sloping bottom, an arcuate abutment situated between the front and rear ends of 20 said furnace and subtending a large angle so that the gap between its ends is narrow and located at the lower part thereof, said gap extending to the floor of the furnace, a fuel nozzle having a flaring annular orifice 25 adapted to discharge a hollow stream of pulverized solid fuel against said abutment and a deflector in said nozzle adapted to prevent discharge of fuel into the gap in the aforesaid abutment.

30 4. In a steam generator, a cylindrical furnace having at its forward end an extension projecting beyond the front end of the steam generator, said furnace and extension being lined with refractory material and having a forwardly and downwardly sloping bottom also of refractory material to facilitate the passage of molten slag over the 35 same, an abutment of arcuate shape ar-

ranged between the front and rear ends of said furnace, the ends of said abutment being arranged to form a centrally disposed narrow gap adjacent to and extending to the floor of said furnace so that said abutment will not impede the passage of slag and a fuel nozzle having a tubular flaring outlet adapted to direct pulverized solid fuel in the form of a backwardly and outwardly spreading hollow stream against said abutment.

5. In a steam generator, a cylindrical furnace having at its forward end an extension projecting beyond the front end of the steam generator, said furnace and extension being lined with refractory material and having a forwardly sloping bottom to facilitate the 50 passage of molten slag over the same, an abutment of arcuate shape arranged between the front and rear ends of said furnace, the ends of said abutment being arranged to form a centrally disposed narrow 55 gap adjacent to and extending to the floor of said furnace so as not to impede the passage of slag, and a pulverized solid fuel discharging nozzle terminating within the said forward extension of the furnace and 60 having a flaring annular orifice adapted to discharge a backwardly and outwardly spreading hollow stream of pulverized solid fuel against said abutment and a deflector 65 in said annular orifice adapted to prevent discharge of fuel into the gap in the said abutment.

Signed at American consulate, Southampton, England, this twenty-sixth day of January, 1920.

THORNYCROFT DONALDSON.
